PANTY HOSE

Clyde A. Berry, Valdese, N.C., assignor to Pilot Research Corporation, Valdese, N.C., a corporation of North Carolina

Filed Mar. 27, 1967, Ser. No. 6,382

Term of patent 14 years

(Cl. D2—7)

FIG-1

FIG-2

FIG-3

FIGURE 1 is an isometric view of a panty hose showing my new design, the front and back of the panty portion being folded inwardly;

FIGURE 2 is an isometric view thereof with the panty portion in an open position; and

FIGURE 3 is an isometric view of the side opposite that shown in FIGURE 2.

The characteristic feature of my design resides in the overall appearance provided by the combination of the upper panty hose portion with the depending stocking portions, each of which has a straight-line front edge extending throughout the complete length thereof and a straight heelless lower rear edge extending parallel with the corresponding portion of the front edge, substantially as shown.

I claim:

The ornamental design for a panty hose, substantially as shown and described.
